UNITED STATES PATENT OFFICE.

GEORGE H. GILMAN AND LEE A. KNIGHTS, OF CLAREMONT, NEW HAMPSHIRE, AS-SIGNORS, BY MESNE ASSIGNMENTS, TO SULLIVAN MACHINERY COMPANY, OF BOSTON, MASSACHUSETTS, A CORPORATION OF MASSACHUSETTS.

DRILL-BIT-ROTATING DEVICE.

1,103,002.

Specification of Letters Patent.

Patented July 7, 1914.

Application filed November 21, 1913. Serial No. 802,299.

To all whom it may concern:

Be it known that we, GEORGE H. GILMAN and LEE A. KNIGHTS, citizens of the United States, and residents of Claremont, Sullivan county, New Hampshire, have invented an Improvement in Drill-Bit-Rotating Devices, of which the following description, in connection with the accompanying drawings, is a specification, like characters on the drawings representing like parts.

This invention relates to drill-bit rotating devices for rock drills, and more especially to devices for utilizing the reciprocative movement of the rock drill's piston for imparting a step-by-step rotative movement to the drill chuck.

Our invention, as herein shown and described, is embodied in a rock drill of the hammer type, but it will be understood that the invention is applicable to other types of rock drills as well.

Our invention will be best understood by reference to the following specification, when taken in connection with the accompanying drawings of one specific embodiment thereof, while its scope will be more particularly pointed out in the appended claims.

In the drawings: Figure 1 is a longitudinal sectional view of a rock drill of the hammer type, having a chuck rotating mechanism embodying our invention; Fig. 2 is an enlarged sectional view on line 2-2 of Fig. 1; and Fig. 3 is a sectional view, partly broken away, on line 3-3 of Fig. 2.

Referring to the drawings, and to the embodiment of our invention which we have selected for illustration, we have there shown a rock drill having a cylinder 4, within which is a piston 5, whose reciprocative movement is controlled by a valve 6, which it will be unnecessary here to describe, since it forms no essential part of our present invention.

A rock-cutting drill-bit 7 of any suitable form may be supported and actuated by the piston in any other appropriate manner, but is herein non-rotatably held in a bushing 8, the latter in turn being secured to a rotatable chuck 9. This chuck is herein mounted to turn in a sleeve 10, constituting a casing secured to the front cylinder head 11, the latter in turn being secured to the forward end of the cylinder. The forward end of

the sleeve is herein provided with an inwardly extending shoulder or flange 12, by which the chuck is held against longitudinal movement while being permitted to rotate. The sleeve 10 is herein provided with a chamber 13, constituting a housing for the clutch presently to be described, which serves as a means automatically to rotate the drill, so that during the continued action of the piston hammer, the drill will be caused to execute a step-by-step rotative movement, and whereby, on movement of the piston in one direction, the latter is caused to turn through a partial rotation, while on movement in the opposite direction, it is free to travel without such rotative movement. In order that this partial rotative movement of the piston may act also to rotate the tool, the piston is herein provided with a forward extension 14, which constitutes a hammer bar adapted to strike the inner end of the drill-bit, and is provided with one or more, herein two, grooves or key-ways 15, which are herein straight,—that is to say, they extend parallel with the axis of the piston. In sliding engagement with these grooves, respectively, there are also provided fixed members upon the chuck, such as keys 16, so that while the reciprocatory movement of the piston relatively to the drill is not impeded, its rotative movement enforces a like rotative movement of the chuck and the drill. The several parts thus rotatively joined, that is, the piston, chuck, bushing and drill, are caused to continue their step-by-step rotative movement, during the operation of the drill, by means of the clutch mechanism already referred to.

As herein shown, the reduced forward extension or hammer portion 14 of the piston is provided, in addition to the straight grooves 15, with a pair of helical grooves 17. These grooves receive helical keys, or teeth, 19, which conform to the shape of, and have sliding engagement with, the helical grooves, and are formed on or appropriately secured to a ring 20, through which the hammer portion of the piston works or slides, during its reciprocatory movement. By this means, the ring 20 and hammer bar of the piston are so connected that as one is held against movement in one direction, the other will of necessity be obliged to turn correspondingly

- in the opposite direction during the reciprocatory movement of the piston. The external surface of the ring 20 is herein smooth or cylindrical in form, and this circumferential surface co-operates with one or more, herein three, rolling bodies 21, which may be and preferably are in the form of cylindrical rollers. These rollers are interposed between the inner ring 20 and an outer ring 22, the latter being provided with one or more recesses 23, herein three, corresponding in number to the rollers to receive the latter. These recesses, or concavities, are inclined circumferentially, so as to provide between the inner and outer members pockets having converging walls, whereby the rollers may be caused, upon movement in one direction, to grip and bind the inner and outer members together; but upon movement in the opposite direction, to permit rotation of the inner member. Interposed between the inner and outer members 20 and 22, is a retainer 24, herein in the form of a ring constituting a cage provided with a plurality of slots 25 to receive the rollers 21, respectively, and carry the latter to and fro as the cage is oscillated. If desired, the outer member 22 may be held against rotation frictionally, but is herein provided with a pair of teeth, or lugs, 26, engaging the corresponding depressions or recesses 27 provided in the forward end of the cylinder head 11. Any appropriate yielding means may be provided tending to rotate the cage 24 in one direction, and thereby urge the rollers 21 up the inclines of their respective concavities into gripping engagement with the opposed surfaces of the inner and outer members. In the present instance, we have chosen to employ for this purpose a spring-pressed pin 28, mounted to slide in a recess 29 provided in a lug 30, projecting laterally from the cage 24. The outer end of this pin engages a wall 31 of a recess 32, formed in the outer member 22 to receive the lug 30. The extent of this recess is such as to allow sufficient play of the lug, so that the cage will carry the rollers to and fro the required distance to cause their gripping engagement with, and disengagement from, the inner and outer members. Herein the pin 28 is provided with a reduced portion 33 encircled by a helical compression spring 34, bearing at one end against the inner end of the recess 29, and at its other end against the head of the pin, thereby serving to press the latter outwardly against the wall 31, and hence constantly tending to turn the cage 24 in a clockwise direction.
- 60 The described mechanism constitutes means to enforce a repeated turning of the piston when traveling in one direction, while allowing it to return in a straight path. During the action of the tool, the drill-bit being pressed against the work offers a slight

resistance to the rotation, while the piston tends to move in a straight line,—that is to say, without rotation. On its forward movement, therefore, through the engagement of its helical grooves with the inner member or ring 20, it tends to rotate the latter in the direction of the arrow shown or the inner ring in Fig. 2, and the rollers 21 are carried toward the deeper portions of their respective concavities, thus permitting free, unrestricted rotation of the ring 20. Hence, there is no tendency to rotate the hammer bar extension of the piston. On its return movement, however, the hammer bar extension tends to rotate the ring 20 clockwise, and since the rollers, upon such movement, become wedged in their cavities, they grip the ring and hold it against rotation, thus enforcing a clockwise movement of the hammer bar extension 14, chuck 9, bushing 85, and drill-bit 7.

It will be observed that the described construction provides an extremely compact rotating device, and, presenting, as it does, comparatively few and simple working parts, it is extremely free from likelihood of breakage or disarrangement. Furthermore, this construction provides an assemblage of parts, the principal elements of which, *i. e.*, the piston, annular rotating member, the chuck and tool, are all united so that they have an intermittent, but continued, rotation in the same direction, it being necessary only to provide clutching or friction parts upon the fixed cylinder adapted alternately to engage and release the rotating member, to effect the turning of the drill. The particular construction described, furthermore, avoids the necessity of placing devices for rotating the piston, such as a rifle bar or the like, within the tool cylinder itself, thereby eliminating a frequent cause for breakage.

While we have herein shown and described one specific embodiment of our invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof.

Having thus described our invention, what we claim and desire by Letters Patent to procure is:

1. In a rock drill, the combination with a cylinder and piston, of a drill chuck, and means for rotating said chuck, said means including inner and outer members, one of which is provided with an inclined concavity and the other with an opposed cylindrical

surface, a retainer interposed between said members, a rolling body carried by said retainer and interposed between said inner and outer members and coöperating with 5 said cylindrical surface and concavity, yielding means tending to rotate said retainer and thereby urge said rolling body up the incline of said concavity into gripping engagement with the opposed surfaces of said 10 inner and outer members, and means for causing the reciprocation of said piston to impart a rotary movement to one of said members.

2. In a rock drill, the combination with a 15 cylinder and a piston having a reduced forward extension, of a drill chuck, and means for rotating said drill chuck, said means including inner and outer members one of which is provided with an inclined concavity and the other with an opposed cylindrical surface, a retainer interposed between said members, a rolling body carried by said retainer and interposed between said inner and outer members and coöperating with 20 said cylindrical surface and concavity, yielding means tending to rotate said retainer and thereby urge said rolling body into gripping engagement with the opposed surfaces of said inner and outer members, said piston 25 extension and inner member being provided one with a helical groove and the other with a tooth engaging therewith, whereby the reciprocation of the piston extension imparts a rotary movement to said inner member.

3. In a rock drill, the combination with a 30 cylinder and piston having a reduced forward extension, of a drill chuck, and means for rotating said drill chuck, said means including inner and outer members one of which is provided with a plurality of inclined concavities and the other with an opposed cylindrical surface, a ring constituting a cage interposed between said members, a plurality of rolling bodies carried by said 35 ring and interposed between said inner and outer members and coöperating with said cylindrical surface and concavities, yielding means tending to rotate said ring and thereby urge said rolling bodies into gripping engagement with the opposed surfaces 40 of said inner and outer members, said piston extension and inner member being provided one with a helical groove and the other with a tooth engaging therewith whereby the reciprocation of the piston extension imparts an oscillatory movement to said inner member.

4. In a rock drill, the combination with a

cylinder and piston, of a drill-bit, and means for utilizing the reciprocative movement of said piston to cause a step-by-step rotative movement to said drill-bit, said means including a roller clutch having a roller cage, a roller, coöperating members engaged by said roller, yielding means tending to rotate said cage in one direction thereby to cause gripping engagement of said clutch, and means operated by reciprocative movement of said piston for causing rotation of one of said coöperating members.

5. In a rock drill, the combination with a cylinder and piston, of a drill-bit, and means for utilizing the reciprocative movement of said piston to cause a step-by-step rotative movement of said drill-bit, said means including a roller clutch comprising one or more rolling bodies, a retainer for said body or bodies, and yielding means tending to rotate said retainer in one direction.

6. In a rock drill, the combination with a 80 cylinder and piston, of a drill-bit, and means for utilizing the reciprocative movement of said piston to cause a step-by-step rotative movement of said drill-bit, said means including a roller clutch comprising inner and 85 outer members, one or more rolling bodies engaging said members, an intermediate member carrying said body or bodies, and a spring operatively interposed between said outer and intermediate members and tending constantly to rotate the latter in one direction.

7. In a rock drill, the combination with a cylinder and piston, of a drill-bit, and means for utilizing the reciprocative movement of 95 said piston to cause a step-by-step rotative movement of said drill-bit, said means including a roller clutch comprising inner and outer members, one or more rolling bodies engaging said members, an intermediate 100 member carrying said body or bodies and provided with a laterally projecting lug, the outer member being provided with a recess in which said lug is disposed, and a spring-pressed pin carried by said lug, engaging a 105 wall of said recess and tending to rotate said intermediate member in one direction.

In testimony whereof, we have signed our names to this specification, in the presence of two subscribing witnesses.
